US0D1031648S

(12) **United States Design Patent** (10) **Patent No.:** **US D1,031,648 S**
(45) **Date of Patent:** **** Jun. 18, 2024**

(54) **WIRELESS CHARGER**

(71) Applicant: **Sihai Yin**, Guangdong (CN)

(72) Inventor: **Sihai Yin**, Guangdong (CN)

(73) Assignee: **DONGGUAN DIANXIAOER ELECTRONIC TECHNOLOGY CO., LTD.**, Dongguan (CN)

(**) Term: **15 Years**

(21) Appl. No.: **29/920,086**

(22) Filed: **Dec. 7, 2023**

(30) **Foreign Application Priority Data**

Oct. 24, 2023 (CN) 202330688948.0

(57) **CLAIM**

The ornamental design for a wireless charger, as shown and described.

DESCRIPTION

FIG. 1 is a front, top and right-side perspective view of the wireless charger showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear, bottom and left-side perspective view thereof; and,

FIG. 9 is another front, top and right-side perspective view thereof, shown in an alternate configuration.

The broken lines throughout the drawing figures depict portions of the wireless charger that form no part of the claimed design.

1 Claim, 9 Drawing Sheets
